END CLOSURE FOR A CONTAINER

Arthur Philip Zundel, Cary, Ill., assignor to American Can Company, New York, N.Y., a corporation of New Jersey

Filed Aug. 14, 1968, Ser. No. 13,138

Term of patent 14 years

Int. Cl. D9—02

U.S. Cl. D9—255

I claim:

The ornamental design for an end closure for a container, substantially as shown.
